CHAIN LINK SIDE BAR, OR THE LIKE, HAVING EXTRUDED LOCKING LUGS

Carl F. Lauenstein, Indianapolis, Ind., assignor to Link-Belt Company, a corporation of Illinois

Application December 13, 1938, Serial No. 245,519

3 Claims. (Cl. 74—250)

This invention relates to new and useful improvements in chain link side bars, or other load bearing elements, which are provided with projecting pin locking lugs, or other projections, produced by extruding or displacing material from the bodies of the elements.

It has been the practice for many years to provide some form of locking lug on chain link side bars for engaging flat surfaces provided on the heads of chain pins to prevent rotation of the pins during joint articulation. It has been a simple matter to form these locking lugs as integral parts of cast or drop forged side bars for the casting molds or forging dies merely have been shaped to provide an appropriate increase in thickness at the location of the lugs.

When forming chain link side bars by the rather recently adopted, less expensive method involving cutting the side bar blanks from bar stock of proper section, shaping the blanks between dies when necessary, for example, in forming offset link side bars, and perforating and broaching the shaped blanks to form pitch or chain pin holes, the locking lugs must be formed from the material of the original section of the bar stock and the lugs are produced by extruding or displacing an appropriate amount of the material laterally of the bodies of the side bars. This lateral displacement of the material to form the projecting locking lugs naturally results in the formation of depressions in the faces of the side bars opposite to the lugs.

Unlike the cast or drop forged lugs, the extruding of lugs from the material of the side bars heretofore has definitely weakened said bars. Considerable trouble has been experienced with side bars having such extruded lugs for failures have developed due to progressive fractures originating in the depressions and progressing outwardly across the side bars. The fact that the extrusion of locking lugs has a weakening effect on side bars was more or less to be expected. However, the percentage of failures and their occurrence so soon after placing a new chain in service indicated that such side bars were weakened to a greater extent than should be expected. Therefore, experiments were conducted to determine if the life of side bars having extruded locking lugs could be materially lengthened.

As all failures resulted from fractures which started at the sides of the depression and progressed outwardly, it was thought that the shape of the tools which formed the lug and the depression and/or the shape of the resultant lug and depression might be the cause. As locking

lugs of approximately square or rectangular shape in plan were employed on cast or drop forged side plates, the same shaped lug was adopted when the extruded lugs were developed and normal shop practice dictated that the depressions should be of the same general shape as the lugs to provide proper grain flow in the material of the side bars during the extruding operation.

Chain link side bars with many different shaped lugs and depressions, including different combinations of the same, were made and tested and, as a result of such experiments, it was ascertained that as sharp corners or angles particularly in the depressions were modified or eliminated, failures became less frequent. A combination depression and lug shape was finally developed which so materially improved the strength of side bars in the region of the depression and locking lugs that side bars having such extruded lugs could be produced which are as strong as side bars without any locking lugs. It was definitely established, therefore, that side bars having extruded locking lugs could be produced which were not rendered less serviceable as a result of the extruding or displacing of material from the body of the side bars.

The primary object of this invention is to provide chain link side bars, or other load bearing elements, with extruded locking lugs without weakening the said bars in the regions of the lugs.

A further object of the invention is to provide a type of depression which is produced in a chain link side bar, or the like, in forming an extruded locking lug, or other projection, without weakening the side bar.

Other objects and advantages of the invention will be apparent during the course of the following description.

In the accompanying drawing forming a part of this specification and in which like numerals are employed to designate like parts throughout the same.

Figure 1 is a plan view of a chain link having a chain pin and a lug which functions to lock the pin against rotation.

Figure 2 is a side elevational view of the link structure shown in Fig. 1.

Figure 3 is a fragmentary, enlarged elevational view of the inner side of the chain link side bar disclosed in Figs. 1 and 2 which is provided with the pin locking lug.

Figure 4 is a longitudinal sectional view taken on line 4—4 of Fig. 3.

Figure 5 is a transverse sectional view taken on line 5—5 of Fig. 4,

Figure 6 is a similar view to Fig. 3 and illustrates for comparison a less effective form of pin locking lug,

Figure 7 is a longitudinal sectional view taken on line 7—7 of Fig. 6, and

Figure 8 is a transverse sectional view taken on line 8—8 of Fig. 7.

In the drawing, wherein for the purpose of illustration is shown the preferred embodiment of this invention, and particularly referring to Figs. 1 and 2, there is disclosed a conventional type of offset chain link of the roller type which has been selected as representative of chain link structures which employ articulating joint pins that are held against rotation by locking lugs. This chain includes a side bar 10, formed without a locking lug, and a side bar 11 which is provided with an extruded locking lug 12. As is conventional with this type of link, a bushing 13 is received in suitable pitch holes formed in the inner ends of the side bars. This bushing functions to exteriorly journal or support a roller 14 and to receive in its bore the chain pin of the next adjacent link. The remaining or outside ends of the side bars are provided with suitable pitch holes 15 and 16 to receive an articulating joint pin 17. As is clearly illustrated in Fig. 2, the head 18 of the pin 17 is provided with one or more flat faces or surfaces 19. The projecting lug 12 engages one of these flat faces of the pin to prevent rotation of the pin during joint articulation of the link.

The side bars of chain links of the character disclosed in Figs. 1 and 2 may be formed either by casting or drop forging operations or by the more recently developed and less expensive method involving cutting the side bars from a piece of bar stock which has a section corresponding to the desired section of the side bars, shaping the side bars when necessary, and perforating and broaching the side bar blanks to form the desired pitch holes. When a locking lug is to be formed on a side bar of the type which is cut from bar stock, it is necessary to form the locking lug from the original material of the side bar blank. An appropriate amount of the material of the blank must be extruded or displaced laterally, by a forcing or forming operation which is performed while the metal of the side bar is either hot or cold, depending upon the thickness of the stock, etc. The extruded lugs are forged or formed, either hot or cold, by means of a die, which is shaped to produce the desired lug formation, and a punch type of tool, which is shaped to produce the depression which must be formed in displacing a sufficient amount of the material of the bar blank to produce the desired, projecting lug.

When the method of producing chain link side bars having extruded locking lugs was adopted, it was only natural that the locking lugs be given the generally square or rectangular shape of the locking lugs which have been conventionally formed on cast or drop forged side bars. Figs. 6 to 8, inclusive, illustrate this first adopted form of extruded locking lugs.

Fig. 6 discloses, by means of dash lines 20, the shape, in plan, of the projecting locking lug 12, see Figs. 7 and 8. Fig. 6 also discloses in full lines, the shape of the depression 22.

Although the method of producing chain link side bars which involved the step of extruding locking lugs was a less expensive way of manu-

facturing chain links, the side bars having the extruded locking lugs were found to be considerably weaker than the side bars which were not provided with such lugs. In any given chain assembly, it was found that many of the side bars having the extruded lugs would fail before a failure would occur in any of the side bars not provided with the locking lugs. It was further determined that the failures always resulted from progressive fractures which started at the corners 23 of the depression 22, see Fig. 6, and progressed laterally outwardly to the side edges of the bars, as indicated by the lines 24. It was decided, therefore, that the shape of the tools and the resultant shape, particularly of the depression 22, might be the cause of these failures. Numerous chain link side bars with differently shaped lugs and depressions were made and tested. It was determined that as sharp corners and angles were modified or eliminated, fewer failures occurred and the life of side bars having extruded lugs more closely approached the life of side bars which were not provided with locking lugs.

It will be noted by inspecting Figs. 6 to 8, inclusive, that the depression 22 is provided with sharp corners 25 which extend substantially at right angles to the plane of the face of the side bar. Sharp corners or angles 26 also were formed at the juncture of the side walls and the bottom wall of the depression. The lug 12 also is formed with several sharp corners and angles. It appeared that these sharp corners and angles had a very definite weakening effect and the elimination of such sharp corners or angles definitely lessened the percentage of failures.

Finally, the shape of lug and depression, disclosed in Figs. 1 to 5, inclusive, was developed. The lug 12 and depression 27 are entirely free from all sharp angles and corners. For the major portion of its surface, the depression 27 takes the form of a semisphere which is represented by dash lines 28 appearing in Figs. 4 and 5 principally, and is partially represented by the dash line 28 in Fig. 3. This spherical form of depression is modified at the forward portion of the same to provide the flat surface 29 which is formed in displacing the material of the side bar 11 to form the flat locking surface 30 of the locking lug 12. By inspecting Figs. 4 and 5, it will be seen that rounded relief surfaces 31, 32 and 33 are provided at the various places where the walls of the depression join with the face of the side bar 11. The curved relief surface 33 is formed as a part of a circle represented by the dash lines 34. Fig. 4 also discloses the fact that a sharp corner or angle is avoided at the point where the flat face 29 joins the semi-spherical surface of the depression 27 by the curved surface or relief 35.

The depth of the depression 27, of course, is determined by the amount of material which must be displaced to form the extruded lug 12. Regarding the diameter of the sphere, represented by the dash lines 28 in the several figures, it has been determined that this diameter, so far as chain design is concerned, should not exceed the diameter of the pitch hole 16, although it may equal the pitch hole diameter or be smaller than said pitch hole diameter.

By inspecting Figs. 2 to 5, inclusive, it will be seen that the lug 12 also is free from sharp angles and corners. The edges 36, see Figs. 2 and 5, are formed on flowing curves while the corners 37, see Figs. 2 and 3, are rounded.

Before the form of depression and lug dis-

closed in Figs. 1 to 5, inclusive, was finally adopted as the commercial structure to be substituted for the form of depression disclosed in Figs. 6 to 8, inclusive, a very rigid trial test was made for the purpose of comparing the relative strengths of these two types of side bars. Two chain assemblies, one including side bars of the type disclosed in Figs. 1 to 5, inclusive, and the other including side bars of the type disclosed in Figs. 6 to 8, inclusive, were operated under identical conditions, each of which simulated a 129.8 horsepower drive. The first failure of a side bar of the type disclosed in Figs. 6 to 8, inclusive, occurred after 79 hours of operation. After 89½ hours of operation, failures had occurred in five side bars of the type disclosed in Figs. 6 to 8, inclusive, and the test of this type of side bar was discontinued. The chain assembly made up of links including side bars of the type disclosed in Figs. 1 to 5, inclusive, was operated for 535 hours before the first failure occurred in one of the side bars having a lug and depression of the character disclosed in Figs. 1 to 5, inclusive. However, during this 535 hour test, two of the plain side bars, i. e., side bars 10 of Fig. 1 which are not provided with locking lugs, had failed. This test was continued many hours beyond the 535 hour point when the first side bar with an extruded lug failed, but no more failures occurred in extruded side bars. The test finally had to be discontinued because other parts of the chain assembly had become so badly worn that the assembly could not have been employed longer as a commercial installation. In comparing the times at which the first failures occurred in these two different types of extruded side bars, it will be seen that the side bars of the character disclosed in Figs. 1 to 5, inclusive, operated close to seven times that of the assembly including extruded side bars of the type disclosed in Figs. 6 to 8, inclusive. As no additional failures occurred in side bars of the character disclosed in Figs. 1 to 5, inclusive, there are no figures to compare with the additional five side bar failures of the type disclosed in Figs. 6 to 8, inclusive. As two plain side bars failed in the 535 hour test, while only one extruded side bar failed, it would appear obvious that extruded side bars of the character disclosed in Figs. 1 to 5, inclusive, are not any weaker than side bars having no extruded lugs.

Although I have selected a chain link side bar to illustrate the advantages of the form of extruded lug disclosed in detail in Figs. 1 to 5, inclusive, it is to be understood that I do not desire to limit my extruded lug development to chain links, because there are many other load bearing elements, such as shackles, clevices, and the like, which employ articulating joint forming pins that should be held against rotation during joint articulation, and in which the strength of the load bearing element may be materially reduced by the use of an improperly shaped depression resulting from the formation of an extruded, pin locking lug.

In attempting to arrive at a satisfactory explanation for the increased strength and fatigue resistance possessed by the extruded side bars of Figs. 1 to 5, inclusive, over the side bars of Figs. 6 to 8, inclusive, it was at first decided that there was a considerably smaller amount of stress concentration in the improved side bar and that the straight edges formed on the punch type of tool which is employed for producing the extrusion of the type disclosed in Figs. 6 to 8, inclusive,

must have a tendency to shear the metal in making the depression with its sharp corners and angles. However, after more mature consideration, it appeared that the increase in life due to the use of the semi-spherical tools was out of all proportion to what might be expected from merely rounding off sharp corners and angles. The following additional explanation, therefore, is given:

It is customary to assemble chain pins in the pitch holes of side bars by a press fitting operation. The pitch hole diameters are usually from .003 of an inch to .005 of an inch smaller than the diameter of the chain pins. Under conditions such as are found in side bars having extruded locking lugs closely positioned with respect to the pitch holes, there is necessarily more metal in some portions of the hole circumference than at others, and the metal displaced by the press fitting will naturally go to the side of the pitch hole which presents the least resistance or which has the least amount of metal. In chain link side bars of the character embodying this invention, the least amount of metal is located between the pitch hole and the depression, formed in extruding the locking lug. The press fit, therefore, tends to force this pin wall into the depression.

In the old design of side bar shown in Figs. 6 to 8, inclusive, with the sharp corners or angles at the base of the depression, press fitting of the pin in the pitch hole will tend to produce a pre-loading of shearing stress at the angle formed by the side walls and the bottom of the depression. This condition, when added to the normal chain stresses, causes overloading and failure.

In the improved form of extruded side bar disclosed in Figs. 1 to 5, inclusive, there are no sharp corners or angles and the rounded surface 35 joins the flat face 29 with the semi-spherical wall of the depression. Due to the location of the semi-spherical depression with respect to the flat face 29, the low point of the depression is not located at the line of connection between the flat face 29 and the curved wall of the depression but is located rearwardly or in spaced relation to the flat face 29. Therefore, stress concentration at the base of the flat face 29 is not so great as with the side bar structure disclosed in Figs. 6 to 8, inclusive, and failures do not occur when the chain is subjected to normal loads.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. In a load bearing element, such as a chain link, the improvement which comprises a side bar having an aperture, a pin having a head formed with a flat surface received in said aperture, a lug projecting from a face of the side bar and having a flat face formed thereon adapted to engage the flat surface of the pin head to prevent rotation of the pin, and a depression formed in the body of the bar as a result of displacement of material of the bar to form said projecting lug, said depression, with the exception of a flat wall portion, having the shape of a semisphere with its diameter not exceeding the diameter of the pin aperture.

2. In a load bearing element, such as a chain

75

- link, the improvement which comprises a side bar having an aperture, a pin having a head formed with a flat surface received in said aperture, a lug projecting from a face of the side bar and having a flat face formed thereon adapted to engage the flat surface of the pin head to prevent rotation of the pin, and a depression formed in the body of the bar as a result of displacement of material of the bar to form said projecting lug, said depression being free from sharp angles and corners and, with the exception of a flat wall portion, produced in forming the flat face on said lug, having the shape of a semisphere which is arranged so as to locate the low point of the depression in spaced relation to said flat wall.
3. In a load bearing element, such as a chain link, a side bar having an aperture, a pin, having a head formed with a flat surface, press fitted in said aperture, a lug projecting from the face of the side bar in close proximity to said aperture and having a flat face formed thereon

adapted to engage the flat surface of the pin head to prevent rotation of the pin, and a depression formed in the body of the bar as a result of displacement of material of the bar to form said projecting lug, said depression having a flat wall portion on the side of the depression closest to the aperture and arranged on a plane parallel to the plane of and produced in forming the flat face on said lug, the remainder of the depression taking the shape of a semisphere which is joined to the flat wall portion of the depression and to the adjacent flat outer face of the side bar by rounded surfaces, the semispherical portion of the depression being arranged so as to locate its low point in spaced relation to the flat wall portion of the depression to thereby lessen stress concentration where the flat wall portion and the semispherical portion of the depression are joined.

CARL F. LAUENSTEIN.
